UNITED STATES PATENT OFFICE.

FRANK W. CHRISTY, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENER-INSERTING MACHINE.

1,315,211.

Specification of Letters Patent.

Patented Sept. 9, 1919.

Application filed December 31, 1917. Serial No. 209,739.

To all whom it may concern:

Be it known that I, FRANK W. CHRISTY, a citizen of the United States, residing at Beverly, in the county of Essex and State of Massachusetts, have invented certain Improvements in Fastener-Inserting Machines, of which the following description, in connection with the accompanying drawings, is a specification, like reference characters on the drawings indicating like parts in the several figures.

This invention relates to fastener inserting machines and more particularly to the operating mechanism thereof. For the sake of illustration, the invention is here shown as applied to the punch lever of an eyeleting machine, but it will become obvious from a more complete consideration of this example that it is in no respect so limited.

In one type of eyeleting machines, of which the Perfection eyeleting machine is a notable example, the punch lever is movable toward and away from the work and is also movable laterally into and out of operating position. Actuation of this lever for movement toward and away from the work is effected by means of an actuating member comprising a horizontally supported bar passing through a slot in the punch lever. Because of the variations in the angular relations of these members, difficulty has been experienced by reason of the binding thereof in said slot.

One object of the invention is to improve the construction of the operating connection between such an actuating member and an operating lever in order to secure freedom of movement while maintaining an unyielding union.

The features of the invention will become apparent from a consideration of the following description of a specific illustrated embodiment. In the drawings,—

Figure 1 is an angular perspective of a fastener inserting machine in which the invention has been applied to the punch lever;

Fig. 2 is a side view of this lever and its actuator;

Figs. 3 and 4 are front and top views of this lever in the same position; and

Fig. 5 is a fragmentary vertical section through the lever and its actuator taken lengthwise of the lever and showing the operating connection.

The fragment of a machine shown in Fig.

1 is the well known Perfection eyeleting machine having a work table 10, a presser foot 12, an eyelet raceway 14 and top and bottom sets 16 and 18. The top set is carried upon a lever 20 while the bottom set is mounted in a plunger actuated by a cam 22.

Located alongside the lever 20 is an operating lever 30 carrying a punch 32. This punch lever 30 is movable around a horizontal pivot 34 in a supporting frame 36 which, in turn, is provided with a journal 38 adapted to be associated with a vertical pivot in the frame of the machine. Movement of this supporting frame 36 around its vertical pivot is controlled by the usual spacing mechanism including a slotted plate 40. A die 42 is carried in the forward end of the frame 36 for co-operation with the punch 32. Upwardly projecting ears 44 on the frame 36 assist in guiding the lever 30 to secure registration of the punch and die and to prevent twisting of the lever 30.

In the machine in question, actuation of the punch lever is effected by means of a vertically movable cam operated rod 50 having a forked upper end 52 between whose arms is pivoted a longitudinally arranged bar 54 passing through a slot 46 in the lever 30. A pin 55 extending through the bar and through the fork 52 forms the pivotal connection that enables the bar to turn. Lateral and angular relative displacement of the lever and bar in a horizontal plane is therefore possible and the bar 54 may turn upon its horizontal axis as the lever 30 is tilted around its pivot 34. Turning movement of the rod 50 is prevented by a laterally projecting arm 51. In the previously used construction, the bar 54 bears directly on the surfaces that form the slot 46.

With such a construction, although lateral movement of the lever 30 with respect to the actuating bar 54 is possible, a difficulty arises when the lever is in an extreme position such as is indicated in Figs. 2 to 4. The axis 34 of the lever 30 and that of the bar 54 are then no longer parallel and when the lever is actuated by vertical movement of the rod 50 and hence of the bar 54, the axis of the bar 54 and the vertical plane of the lever 30 no longer maintain a perpendicular or ninety degree relation. This is shown in Fig. 3 and it is so marked that it has been necessary at times, as a temporary expedient, to bevel the sides of the slot 46 to

avoid binding of the connections in consequence of oscillating the frame 36 about the axis of journal 38.

The improvement constituting the subject-matter of the present invention avoids this difficulty and allows freedom of movement while maintaining a rigid connection. The operating connection between the rod 50 and the lever 30 embodies a ball-and-socket structure, the ball element of which includes the bar 54 and ball segments 68, 68. The contacting faces of the bar and segments are flat and parallel to permit the segments to slide freely on the bar. In this sense the ball segments are sliding shoes. The sockets for the ball segments are formed in screws 60 and 62 which are fixed in and carried by the lever 30, being in effect equivalent to integral portions of the lever. Screw 60 is adjustable and is locked by a nut 64. As shown, it is provided with an oil hole 66, and the ball segments and bar 54 are provided with oil holes that register therewith. The bar 54, which constitutes the middle zone of the ball element, keeps the segment members 68 seated in their sockets while permitting the segment members to slide thereon as they follow the lever 30. The connection thus afforded is rigid in respect to transmitting the motion of the rod 50 to the lever 30, but is a zero quantity in respect to all other motions, and the binding and straining heretofore encountered in machines of this type are wholly eliminated.

In the operation of the machine, a hole is punched in the work by means of the punch 32 and its coöperating die 42, and for this purpose the punch lever is moved downwardly by the actuating rod 50 which receives motion from a cam upon the main shaft of the machine. This punch lever is then raised and moved laterally to the right, as viewed in Fig. 1, in order to allow the lever carrying the top set to be rotated about its vertical axis in order to bring the top set 16 into alignment with the hole just punched in the work. The top set then advances into this hole and moves laterally into alignment with the bottom set 18, feeding the work by reason of its engagement therewith. The bottom set then presents an eyelet to the work and clenches the same against the upsetting surface provided upon the top set. As the lever carrying the upper set moves laterally to feed the work and to bring the top set into alignment with the bottom set, the punch and die are returned to the position which they previously occupied, and the machine is ready for a repetition of its cycle. It will be noted that the operating connection between the actuating rod 50 and the lever 30 is maintained in all positions and that the operating connections between the lever and the horizontal bar 54 are constructed and arranged to allow these

members to assume freely angular relations which are different from a ninety degree relation without causing straining or binding of the intermediate parts.

It will be understood that the terms "horizontal" and "vertical" as used in the specification and claims are merely for convenience in defining the relative positions or locations of parts and should not, in any case, be construed as limitations. The invention is broader than the particular illustrated embodiment and may be applied wherever the problem occurs.

Having thus described my invention, what I claim as new and desire to secure by Letters Patent of the United States is:

1. In a fastener-inserting machine, a tool-lever arranged to execute universal angular movement, a reciprocatory actuating element, and means forming operating connection between said actuating element and said lever between the ends of the latter, said means being constructed and arranged to transmit all of the motion of said element positively to the lever and to permit freedom of universal angular motion of the lever relatively to the actuating element.

2. In a fastener-inserting machine, a tool-lever arranged to execute universal angular movement and having a hole extending transversely, a reciprocatory actuating element, and means arranged to occupy said hole and forming operating connection between said actuating element and the lever, said means comprising a three-zone ball element the middle zone of which is pivotally connected to said actuating element to turn about an axis, and the two outer zones of which are free to slide relatively to the middle zone, said lever having sockets in which said outer zones are seated and free to rock.

3. In a fastener inserting machine, a tool-carrying lever mounted for universal angular movement around a horizontal axis and a vertical axis, an operating bar slidably arranged to rock on a horizontal axis, ball-and-socket connectors interposed between said bar and said lever to rock with and slide relatively to the bar, and means for moving said bar vertically to actuate said lever.

4. In a fastener-inserting machine, a tool-lever arranged to execute universal angular movement and having a hole extending transversely, a reciprocatory actuating element, and means arranged to occupy said hole and forming operating connection between said actuating element and the lever, said means comprising two coöperative ball segments having flat faces confronting but separated from each other, coöperative socket portions carried by the lever and co-acting with said ball segments respectively, and a bar carried by said actuating element and arranged between said ball segments to

keep the latter seated in their respective sockets, the segment-engaging faces of said bar being flat and parallel to permit free sliding of the segments thereon, and said bar being pivotally connected to said actuating element to turn about an axis intersecting the bar.

5. In a fastener inserting machine, an operating lever movable in a vertical plane, a horizontally disposed vertically movable actuator bar for said lever adapted to assume various angular relations with respect to said lever, and displaceable connector members interposed between the bar and confronting faces of the lever, said connector members being constructed and arranged to allow variation from a perpendicular relation of the bar and lever.

6. In a fastener-inserting machine, a tool-lever arranged to execute universal angular

movement and having a hole extending through it transversely, a three-part ball element including segmental outer members and an intermediate member, said ball element being arranged in said hole, said lever 25 having confronting socket portions co-acting respectively with said outer members, one of said socket portions being adjustable to take up loose play between the three parts of the ball element and between the latter 30 and the lever, the contacting surfaces of said three parts being flat and parallel, said intermediate member projecting beyond the lever at both sides, and movable means pivotally connected to said intermediate member 35 to move the latter bodily and thereby to oscillate the lever.

In testimony whereof I have signed my name to this specification.

FRANK W. CHRISTY.
